The ornamental design for flatware, as shown and described.

DESCRIPTION

FIG. 1 is a top plan view of a new ornamental design for flatware embodied as a knife, the opposite bottom plan view being a mirror image.

FIG. 2 is a side elevation view thereof, the opposite side elevation view being an identical image.

FIG. 3 is an end view thereof, shown from the end of the handle.

FIG. 4 is an end view thereof, shown from the opposite end of that shown in FIG. 3.

FIG. 5 is a cross-sectional view taken along section line 5-5 of FIG. 1 to illustrate the peripheral shape of the article at the cross-section.

FIG. 6 is a cross-sectional view taken along section line 6-6 of FIG. 1 to illustrate the peripheral shape of the article at the cross-section; and,

FIG. 7 is a cross-sectional view taken along section line 7-7 of FIG. 1 to illustrate the peripheral shape of the article at the cross-section.

The broken lines in the drawings are included for purposes of illustrating portions of the article that form no part of the claimed design.
